AERIAL FIRE EXTINGUISHER

James H. Rust, La Habra, Calif.

Application June 4, 1954, Serial No. 434,461

3 Claims. (Cl. 169—1)

This invention relates generally to fire extinguishing equipment and more particularly to an improved method and apparatus for aerial fighting of fires located in remote regions where an adequate supply of water or other conventional fire fighting means are not available.

In the case of mountain brush, forest fires, or heavy industrial fires, such as oil wells, for example, considerable destruction results from the fact that a source of water is not readily available nor are the means for transporting water, if close at hand, efficient. In the past, it has been proposed to fight such fires by means of aerial bombs or cartridges adapted to be dropped from aircraft. Upon striking the ground, these fire fighting bombs will explode and spread smothering chemicals over a substantial area of the blaze.

The principal difficulties with the above method are, first, lack of control of the bomb after it has been released from the aircraft decreasing the chances of striking at the center of the blaze, and, second, the lack of a sustaining action in smothering the flames. In other words, after the chemicals have been released, the flames may be temporarily subdued, but without a sustaining action, sufficient heat will usually remain in the area to re-ignite the fire.

With the foregoing in mind, it is a primary object of the present invention to provide an improved method and apparatus for extinguishing fires from the air.

More particularly, it is an object of the invention to provide an aerial fire fighting system in which a sustaining fire extinguishing action takes place with minimum man power and equipment.

Still another important object in this regard is to provide a method and apparatus for fighting fires from the air in which the positioning of the fire fighting equipment is at all times under human control, whereby the action may be concentrated in the more serious areas of the fire.

Another object is to provide a method and means for extinguishing fires which does not rely on a large water supply.

In accordance with the method of the present invention, a pressure container or bulb filled with suitable chemicals under high pressure is adapted to be secured to the end of a cable including a swivel joint and lowered from an aircraft, preferably a helicopter. The helicopter is flown over the fire area with the bulb suspended a few feet from the ground. Suitable triggering mechanism opens a discharge valve in the bulb releasing the chemicals through nozzles oriented to provide jet sprays in various directions. The jet action of the sprays serves to rotate the bulb insuring that the chemicals are sprayed uniformly over a relatively large area. The cable from the helicopter can be raised or lowered and the plane flown to transport the pressure bulb to the most serious areas of the fire. When the pressure bulb is empty, the aircraft returns to a given location where other bulbs are stored, and while still hovering in the air, the empty bulb may be detached and a new one connected to the cable. The

2

helicopter can then immediately return to the fire and continue the attack.

The fire fighting pressure bulb for carrying out the method of the invention is preferably in the form of a metal sphere, although any other shape of container may, of course, be used. The sphere is provided with a triggering means at its lower end for opening a valve communicating with the interior of the sphere and the chemicals therein under pressure. Surrounding the valve, there is provided an annular manifold chamber from which suitable pipes or hoses lead upwardly outside the sphere to strategically located nozzles. These nozzles are oriented to project the chemical spray in directions having like tangential components to the sphere surface, whereby a jet reaction obtains for rotating the sphere.

It is important in connection with the above, that the triggering mechanism for permitting the discharge of the chemicals within the sphere, be positive in action and substantially foolproof in operation whereby the chances of accidental opening of the valve are minimized.

In one embodiment of the invention, this valve is triggered by a probe positioned to contact the ground upon reeling out sufficient cable length to lower the pressure bulb within striking distance, and then hoisting up the cable after the triggering has been accomplished a desired distance for maximum effectiveness in fighting the fire. Once the valve has been opened, the construction is such that it cannot be closed. In a second embodiment, the heat of the fire is employed to operate the discharge valve.

A better understanding of the invention will be had by referring to the accompanied drawings, in which:

Figure 1 is a schematic view showing the fire extinguishing system of the invention in operation;

Figure 2 is an enlarged cut-away perspective view of a preferred form of pressure bulb;

Figure 3 is an elevational cross-section taken in the direction of the arrows 3—3 of Figure 2;

Figure 4 is another elevational cross-section taken in the direction of the arrows 4—4 of Figure 2 showing a first embodiment of the discharge valve assembly in closed position;

Figure 5 is a view similar to Figure 4 showing the discharge valve in open position;

Figure 6 is an elevational cross-section of a second embodiment of the discharge valve in closed position; and

Figure 7 is a view similar to Figure 6 showing the valve in open position.

Referring to Figure 1, there is indicated schematically a typical forest or brush fire 10. In accordance with the method and apparatus of the present invention, an aerial fire extinguisher in the form of a pressure bulb 11 is filled with fire extinguishing chemicals under pressure. This bulb is extended from a cable 12 secured to a suitable winch 13 in a helicopter 14 and is adapted to be triggered to eject fire smothering sprays 15, 16, 17, and 18 in different directions, as shown. The position of the pressure bulb 11, both as to elevation and lateral location, are easily controlled by the winch in the helicopter and position of the helicopter, respectively. Thus, with the above arrangement, the pilot of the helicopter can fly over the most serious areas of the fire and position the pressure bulb 11 for a sustaining attack on such areas.

As shown more clearly in Figure 2, a preferred form of pressure bulb is in the shape of a sphere whereby a maximum volume of fire fighting chemical may be contained within a minimum of physical space. In this embodiment, the sprays 15, 16, 17, and 18 are ejected from nozzles 15', 16', 17', and 18', distributed about the periphery of the sphere, preferably adjacent the mid-positions thereof. As shown by the arrows, the nozzle 15'

is arranged to direct its spray partially upwardly and partially tangentially to the sphere 11, while the nozzle 16' ejects the spray partially downwardly and partially tangentially. Similarly, the nozzles 17' and 18' direct their spray partially downwardly and partially upwardly, respectively, each having a tangential component opposite in direction respectively to the tangential component of the nozzles 16' and 15'. The tangential components of the four sprays result in a reaction force on the sphere tending to rotate the latter about a swivel joint 26, in a clockwise direction as viewed from above.

Suitable conduits or pipes connected to these nozzles are shown at 19, 20, 21 and 22, respectively, and lead to a central annular manifold 23 at the lower end of the sphere. The fire extinguishing chemicals within the sphere indicated at 24, are adapted to pass through a suitable discharge valve and enter the manifold 23 to pass to the various nozzles. Obviously, the nozzles may be located at other positions on the sphere from those shown, and if desired, the conduits or hoses 19, 20, 21, and 22 may be dispensed with and the four nozzles connected directly to the manifold 23. In the latter event, the rotating jet action would not be as effective as in the case where the nozzles are disposed relatively far from the sphere axis.

The chemicals within the sphere 11 may comprise water under pressure or any of the dry chemicals, such as bicarbonate derivatives or vaporizing liquids in the form of chlorides and bromides. These chemicals are conveniently introduced in the sphere by means of an inlet valve structure 25.

Referring now to Figure 3, the details of the inlet valve 25 and swivel joint 26 are shown. The inlet valve may be located anywhere on the sphere surface but is preferably disposed at the top adjacent the cable coupling. This inlet structure comprises a valve supporting plate 27 welded over a suitable opening in the sphere surface. A valve housing 28 is threaded to the plate support 27 in sealing relationship as shown. The valve itself comprises a valve stem structure 29 threaded into the member 28, and a branch passage 30 communicating with an interior space about the valve stem. The end of the branch 30 is threaded to receive a hose. To fill the sphere with suitable chemical solutions, the valve stem 29 is threaded inwardly to unseat the valve face 31, whereby chemicals may be pumped into the sphere through the hose connection 30. When the sphere has been filled under high pressure, the valve stem 29 is threaded outwardly to seat the valve 31 and the supply hose then uncoupled from the hose connection 30.

The swivel joint for the sphere 11 may, of course, be disposed in the cable 12 itself and need not form a part of the spherical bulb structure. In the embodiment shown in Figures 1 to 3, however, this swivel joint is made a part of the sphere structure and, as shown, comprises a base supporting plate 32 welded to the top of the sphere. A suitable bearing block 33 is in turn bolted to the plate 32 and serves to house a cylindrical bearing 34 rigidly screw threaded to an eyelet 35. Suitable ball bearings 36 disposed between the bearing block 33 and cylindrical bearing 34 permit substantially frictionless swiveling action to take place therebetween. The coupling of the end of the cable 12 to the eye 35 is effected by a simple removable hook means 37, whereby an empty sphere may be readily removed and a filled sphere attached.

Figures 4 and 5 show in detail the discharge valve and actuating mechanism for releasing the pressurized chemicals within the sphere 11 to the manifold 23 and various nozzles. Referring specifically to Figure 4, the bottom of the spherical bulb 11 is provided with a circular opening 38 over which is secured a manifold housing 39 for the manifold 23. A valve block 40 fits within the housing 39 and is held therein by means of a retaining

ring 41. Suitable seals between the valve block 40 and the housing 39 are effected by sealing rings as shown. At the upper portion of the valve block 40, there is disposed a valve head 42 having a downwardly extending stem 43. The lower end of stem 43 rests on the upper end of a valve stem support 44, supported by a spherical bearing 45 and constituting a rigid extension of an actuating triggering probe 46. The spherical bearing 45 fits within a corresponding spherical socket in the lower end of the valve block 40, as shown. Wobbling movement of the probe 46 is temporarily prevented by means of an annular collar 47 pinned to the probe 46 by a pin 48. Pin 48 in turn is provided with a withdrawing means in the form of a J bar 49 passing through an opening in the manifold housing 39.

In operation, just prior to take off of the helicopter, the J bar 49 is pulled to remove the pin 48 whereby the annular collar 47 drops off from the probe 46. The probe is then positioned to swivel about its spherical bearing 45. However, the pressure of the chemicals 24 within the sphere 11 will tend to hold the probe 46 substantially vertical through forces transmitted by the valve stem 43. The helicopter is then flown over the fire area and the spherical bulb 11 lowered until the projecting probe 46 scrapes against the ground. This scraping action tends to cant the probe as indicated in Figure 5, thereby permitting the valve head 42 to drop out of position. The chemicals 24 will then pass through the opening 38 into the manifold chamber 23 and through the various conduits or hoses, such as 22, to the respective nozzles. With the valve stem support 44 on the end of the triggering probe 46 no longer in engagement with the valve stem 43, there is no way in which the valve head 42 can be accidentally replaced, and thus continued passage of the chemicals out of the sphere is assured. When the contents of the sphere have been expelled and the sphere returned to its operating base, the valve may be reset or, in the event the valves are expendable, a new, preset, valve structure substituted in the manifold housing 39 by simply removing the retaining ring 41.

Figures 6 and 7 show a different type of discharge valve apparatus which may be used in place of the discharge valve shown in Figures 4 and 5. In the embodiment of Figures 6 and 7, the heat of the fire is relied upon to open the discharge valve rather than an actuating probe.

As shown in Figure 6, the opening 38 in the lower portion of the spherical bulb 11 is covered by a circular manifold housing 50 threaded supporting a valve casting 52 comprising a valve head 53 and valve stem 54. At the lower end of the valve casting 52, there is threadedly secured a cylindrical member 55 having an annular flange 56 adjacent its upper end. The lower portion of the cylindrical member 55 is reduced in diameter as at 57 and is arranged to receive an annular flanged support 58 in sliding engagement. Between the flanged portion 56 of the cylindrical member 55 and the support 58, there is provided an annular bellows 59 adapted to expand when subjected to heat. The lower support 58 is biased upwardly against the bottom portion of the annular bellows 59 by a compression spring 60 supported at its lower end by a collar 61 threaded to the lower reduced diameter portion 57 of the cylindrical member 55. This collar is pinned to the valve stem support rod 62, as shown at 67.

An annular interior recessed portion in the cylindrical member 55 accommodates an actuating rod 62, the upper end of which supports the valve stem 54. A compression spring 63 within this recess is adapted to bias the actuating rod 62 downwardly. Downward motion of the actuating rod 62 is prevented, however, by a ball 64 disposed in an annular recess 65 in the rod 62. An annular cavity 66 in the collar 58 is normally positioned above the ball 64, as shown.

In operation, the pin 67 is removed to permit free sliding motion of the actuating rod 62 within the cylin-

drical member 55 and thereby place the apparatus in condition for operation. The spherical pressure bulb 11 is then flown over the fire area. Heat from the fire will expand the bellows 59 urging the collar 58 downwardly until the annular internal cavity 66 in the collar is juxtaposed the ball 64 in the recess 65 of the actuating rod 62. This position of the parts is clearly shown in Figure 7. The ball 64 will fall into the annular cavity 66 and the rod 62 will then be free to move downwardly under action of the spring 63 and the normal pressure exerted thereon by the chemicals 24 through the valve stem 54 and valve head 53. Downward movement of the actuating rod 62 permits the valve head 53 to move downwardly and provide a communicating space between the opening 38 and the annular manifold 51, as shown in Figure 7. The pressure of the chemicals 24 will be sufficient to hold the valve open.

The discharge operated valve shown in Figures 6 and 7 is advantageous for brush fires on sloped mountains wherein it may not be convenient to actuate a probe such as shown in Figures 4 and 5.

It will be appreciated at once from the above description that both of the embodiments of the discharge release valve are positive in operation and substantially foolproof from a safety standpoint. In neither instance is there any possibility for accidental discharge of the chemicals within the sphere as long as the locking pin 48, in the case of valve shown in Figures 4 and 5, and 67 in the case of the valve shown in Figures 6 and 7 are in position. Once these pins are removed, however, the pressure bulbs 30

are thus in condition for instant triggering. Because of the distribution and direction of the nozzles on the spherical bulb, the spraying chemicals not only effect rotation of the sphere to insure a substantially uniform distribution of such spray, but will cover a relatively large area for a sustained period. Further, the pressure bulbs may be used many times and there is thus avoided the loss of fire fighting equipment as has characterized prior art aerial devices.

Modifications within the scope and spirit of the method 40 and apparatus described will occur to those skilled in the art. The present invention is therefore not to be thought

of as limited to the specific embodiments disclosed for illustrative purposes.

I claim:

1. Apparatus for aerial fire fighting comprising: a container; means for introducing fire fighting chemicals into said container under pressure; means for suspending and moving said container over different portions of a fire area; and triggering means carried by said container for releasing said chemicals whereby a sustained discharge of the chemicals over the fire area is effected, said triggering means including a probe element projecting from the bottom of said container in a given direction and valve means communicating with the interior of said container and operatively connected to said probe element whereby said valve means will be opened responsive to tilting of said probe member from said given direction.

2. Apparatus as set forth in claim 1 which includes swivel joint means cooperating with said means for suspending the container whereby said container may rotate, and nozzle means on said container spaced from the axis of rotation of said container for discharging said chemical, said nozzle means being oriented to eject said chemicals in a direction having a tangential component to the surface of said container whereby a reaction force is established for rotating said container.

3. Apparatus as set forth in claim 2 wherein said probe element is mounted in the lower portion of said container for tilting movement and said valve means includes a valve stem, the upper end of said probe engaging an end portion of said valve stem to hold said valve means closed when said probe is in a first position, the other end of said probe projecting away from said container whereby tilting movement of said probe disengages said one end from said valve stem so as to effect opening of said valve means.
